Des. 100

W. P. Breton David Stuart & Samuel H. Sailor
County of Philadelphia, Pennsylvania.
Letters Patent (Design No. 100) dated 27 October 1846.

The schedule referred to in these Letters Patent and making
part of the same.

To all whom it may concern Be it known that we the undersigned
David Stuart and Samuel H. Sailor all of the County of Philadelphia
in the State of Pennsylvania has invented or produced a new ornamental
Design for a Cast Iron Stove Plate which may be used to ornament a
variety of Stoves in connection with other plates and do hereby declare
that the following is a description of the Design.

2

Des. 100

The general form is an oblong-square the edges are ornamented with scroll leaf & flower work and at A A A A and each corner is ornamented with a Shell B B B B the center is a raised panel of flower and leaf work in rich profusion with a space for a vase foot left in its proper place at C, a said space may have a collar raised around it to receive a stone pipe

We have thus described the Design which we wish to patent and do hereby claim the exclusive right to the same for stone plates as we have laid them out and displayed them on the plate
